United States Patent Office

Des. 211,024
Patented May 14, 1968

211,024

KEYBOARD INPUT STATION

Robert Howard, 20 Redwood Drive, Roslyn, N.Y. 11576

Filed May 31, 1967, Ser. No. 7,316

Term of patent 14 years

(Cl. D26—5)

FIGURE 1 is a perspective view of a keyboard input station showing my new design;

FIGURE 2 is a perspective view of an alternative embodiment of a keyboard input station showing my new design.

The broken lines are for illustrative purposes. The views diametrically opposite those shown are substantially similar in appearance.

I claim:

The ornamental design for a keyboard input station, as shown and described.
